UNITED STATES PATENT OFFICE.

FRANK B. PEEBLES, OF SYRACUSE, NEW YORK, ASSIGNOR TO THE LAMSON COMPANY,
OF SYRACUSE, NEW YORK, A CORPORATION OF MASSACHUSETTS.

SAFETY DEVICE FOR CONVEYER SYSTEMS.

Application filed April 19, 1933. Serial No. 633,132.

To all whom it may concern:

Be it known that I, FRANK B. PEEBLES, a citizen of the United States of America, and resident of Syracuse, in the county of Onondaga and State of New York, have invented new and useful Improvements in Safety Devices for Conveyer Systems, of which the following is a specification.

This invention pertains to overhead conveyer systems of the kind employed in packing establishments, warehouses and the like for transporting heavy articles of merchandise from point to point, and relates more particularly to safety devices for use in such a system.

In such systems it is common to provide sidings onto which wheeled carriers or trolleys may be diverted from the main track for loading, unloading, or inspection of the article or articles carried by them. From the sidings, the carriers are transferred back to the main track over a normally closed switch point, which, however, is opened or swung away from the main track by carriers passing along the latter. If, at the instant the switch point is open, a carrier moves from the siding onto the switch point, it may run off the end of the latter with disastrous results, either to the suspended merchandise or to workmen stationed below.

A principal object of the present invention is accordingly to provide an automatic safety appliance for use in such a conveyer system, operative to prevent accidental escape of a carrier from an open switch point leading to the main track.

In the accompanying drawings, a preferred form of the invention is illustrated by way of example and in such drawings,

Fig. 1 is a fragmentary plan view, to small scale, illustrating a typical conveyer system to which the present invention is applicable;

Fig. 2 is a fragmentary plan view, to larger scale illustrating a portion of such a conveyer system having the present invention applied thereto;

Fig. 3 is a fragmentary plan view, to a scale larger than that of Fig. 2, showing an embodiment of the present invention in detail;

Fig. 4 is a side elevation of the parts shown in Fig. 3; and

Fig. 5 is a fragmentary elevation at right angles to Fig. 4, showing further details.

Referring to Fig. 1, the numeral 1 indicates the end of a continuous conveyer which may extend along a railroad track or a dock, indicated generally by the numeral 2. Branch tracks, of which one is indicated in this view, extend laterally from the main track 1. These branch tracks are preferably continuous, and may comprise the substantially parallel runs 3, 4 respectively which are connected with the main track by the curved track sections 5, 6. The runs 3 and 4 of the branch track may, if desired, extend along and closely parallel to railroad spurs 7 and 8 respectively upon which freight cars C may be placed for loading and unloading. The runs 3 and 4 of the branch track are furnished with sidings 9.

Preferably the main track 1, as well as the runs 3 and 4 of the branch track, are furnished with continuously moving elements such as endless chains, for propelling the article supporting carriers along the tracks, but the sidings 9 need not be furnished with propelling means, so that carriers which are switched onto the sidings 9 may come to rest in a position permitting the convenient loading and unloading or inspection of the article or articles supported by the carriers.

The several tracks, constituting parts of an overhead conveyer system, are conveniently supported from a frame indicated generally by the numeral 10, such frame being constructed in any desired manner and supported upon posts or other structural elements of the building in which it may be installed.

Referring to Fig. 2, the run 4 of the branch track is provided with a movable switch point 11 having actuating mechanism 12 of any desired form indicated generally at 13. This switch point may be set so as to divert carriers passing along the run 4 onto the siding 9 or to permit such carriers to continue along the run 4 as may be desired.

The other end of the siding 9 converges toward the run 4 as indicated at 13. A movable switch point 14 is pivotally secured at 15 to the end of the portion 13 of the siding. Normally this switch point is held in the position shown in Fig. 2 by

means of a spring 16 which resiliently holds the extremity 17 of the switch point substantially in contact with the rail 4.

When a carrier such as 18, moving along the rail 4, approaches the junction of this rail with the switch point 17, it comes into contact with the end of the switch point and moves the latter away from the main rail to a distance sufficient to permit the passage of the carrier, but the switch point springs back immediately after the passing of the carrier and resumes its normal position.

In Fig. 3, a carrier 19 is shown as resting upon the switch point 14, and in this figure the switch point is shown in dotted lines as having been moved away from the rail 4 by the carrier 18 which is moving along the latter. If, under such circumstances, the carrier 19 should continue along the switch point it would drop freely from the end of the latter. In accordance with the present invention the following mechanism is provided for preventing such accidental dropping of the carrier from the switch point.

The frame member 20 which may constitute a part of the supporting frame work 10 is here illustrated as a channel iron having its flanges extending horizontally. An angle iron comprising flanges 21 and 21^a is secured to the web of the channel iron and a flat bar 22 is secured to its outstanding flange 21^a. This bar is bent outwardly and then downwardly at 23, thus providing the offset portion 24 which extends parallel with the outstanding flange of the angle iron. A pin 25 passing through openings in the member 24 and in the flange 21^a of the angle iron provides a bearing for a depending stop supporting member 26. This member is preferably formed from a flat bar which is twisted at 27 to provide a portion 28 lying in a plane at right angles to the frame or pivotal portion of the support.

The lower end of member 28 is bent at right angles to provide the part 29 which lies substantially in a horizontal plane. This part is provided with two or more openings 30 for the reception of bolts 30 which pass through an elongate slot 31 in the extension member 32. This extension member comprises the stop 33 having an end face 36 which is normally spaced from the switch point 14 a sufficient distance to permit the free passage of a carrier along such switch point. The stop 33 is recessed at 34 to provide a carrier engaging abutment shoulder 35.

A flat bar 37 is secured to the flange 20 of the angle bar and this bar is bent outwardly and then downwardly at 38 to provide the depending portion 39 extending parallel with the lower part 28 of the support 26. At its lower end the member 39

is bent at right angles to provide a stop 40 normally spaced a slight distance from the member 28.

A flat bar 41 is secured to the opposite side of the flange 20 and after being bent in its own plane at 42, (Fig. 5) extends downwardly at 43 substantially parallel with the parts 28 of the support. At its lower end the member 43 is bent to provide a stop 44 opposite the stop 40 and also normally spaced from the member 28.

Usually the end portion 13 of the siding 9 is inclined downwardly toward the switch point 14 so that a carrier, such as 19^a, Fig. 4, moving along such portion of the siding 9 tends to approach the junction with considerable velocity. If the switch point occupies its normal position, such a carrier merely runs out onto the main track 4 where it is picked up by the propelling devices and moved outwardly and onto track 1, if desired. If, however, as indicated in dotted lines in Fig. 3, the switch point should be pushed aside by a carrier 18 moving along the main track at the instant that a carrier 19 moves onto the switch point, the abnormal outward position of the latter swings it so near to the stop device that the carrier engages shoulder 35 which prevents its further progress.

As the carrier 18 continues along the main track, it pushes the switch point further and further aside, thus causing the support 26 to swing about its axis until the member 28 engages the stop 40 when it comes to rest holding the carrier 19 against further movement along the switch point.

When the carrier 18 on the main track has entirely passed the switch point, the spring 16 draws the latter back to normal position. If the stop device were stationary, such movement of the switch point might possibly release the carrier 19 from the stop device and the carrier might run off the end of the switch point before the latter had fully closed against the main track. With the present arrangement, however, as soon as the switch point begins to move the frictional engagement of the carrier with the stop shoulder tends to draw the stop member outwardly with the switch point and this movement continues until the member 28 strikes the stop 44. By this time the switch point has nearly closed so that release of the carrier 19 is permissible. The carrier thereupon continues along the switch point, being disengaged from the shoulder 35, and the stop device swings back to its normal position.

While the arrangement disclosed is particularly adapted for use with overhead conveyor systems employing wheeled carriers, it is clear that in its broadest application it is capable of embodiment in other types of rail systems comprising main and branch

tracks with movable switch points for controlling the passage of bodies moving along said tracks. Moreover, while as above stated, it is preferable to mount the stop element in such a manner as to permit it to move to a limited extent, such movement is found not to be necessary under certain conditions of use and may then be dispensed with.

10 I claim:

1. In combination with a pivoted switch point normally operative to direct moving bodies from one track of a conveyer system to another, a movable stop member co-operative with the switch point to prevent movement of bodies along the switch point when the latter occupies one position, and to permit such bodies freely to pass along the switch point when the latter occupies another position, the position of the stop member being unaffected normally by movement of the switch point.

2. A conveyer system comprising a pair of tracks, a pivoted switch point forming a continuation of one track and converging toward the other track, resilient means normally holding the free extremity of the switch point in contact with the last named track but permitting said switch point to move away from said last named track when engaged by a carrier moving along the latter track, and a member normally fixed as respects movements of the switch point and having a stop shoulder so positioned as normally to permit carriers to move freely along the switch point but to engage and stop carriers so moving when the free extremity of the switch point is swung away from normal position.

3. A conveyer system comprising a main track and a converging side track along which carriers move toward the main track, a movable switch point at the intersection of said tracks, means normally operative to hold the switch point substantially in engagement with the main track but permitting it to move away from the main track by engagement with a carrier to permit the carrier moving along the latter track to pass freely, and means to prevent accidental escape from the switch point of a carrier approaching along the branch track when the switch point is moved away from the main track, said means normally being unaffected by movement of the switch point.

4. A conveyer system comprising a main track, a branch track, a switch point constituting an extension of the latter track and movable toward and from the main track, resilient means normally tending to move the switch point toward the main track but permitting it to move away from the main track to permit a carrier to pass along the latter, and an automatically acting stop de-

vice to prevent a carrier from escaping from the switch point when the latter is moved away from the main track, said stop device being independent of and unconnected to the switch point.

5. A conveyer system comprising a main track, a branch track, and a switch point pivotally connected to the latter and converging toward the main track, means normally holding the free extremity of the switch point in substantial contact with the main track but permitting it to swing away from the main track under the action of a carrier moving along the latter, and a stop member ineffective to stop carriers moving along the switch point when the latter is in normal position, but operative to prevent carriers from so moving when the switch point has been moved away from the main track, the position of the stop member being unchanged by movement of the switch point except when a carrier rests upon the latter.

6. A conveyer system comprising converging tracks, a switch point pivotally secured to the end of one track and having its free extremity normally in contact with the other track to deliver the carriers on to the latter, and a movable stop member normally positioned to permit carriers to move freely along the switch point but to stop carriers so moving when the free extremity of the switch point is not in normal position, said stop member normally remaining in the same position regardless of the position of the switch point.

7. A conveyer system comprising a pivoted switch point, means normally holding it in one position but permitting it to move from said position, a movable member having an abutment element adapted to stop carriers moving along the switch point when the latter is in abnormal position, said abutment element normally remaining in the same position regardless of the position of the switch point, and stop elements for limiting movement of the movable member.

8. A conveyer system having a pivoted switch point and a stop co-operable therewith to prevent carriers moving along the switch point from dropping therefrom, said stop being carried by a freely swinging support.

9. A conveyer system having a pivoted switch point movable in a substantially horizontal plane, a support swinging about a substantially horizontal axis, and an arm carried by the support, said arm having relatively adjustable parts, one of said parts having an abutment shoulder disposed adjacent to the switch point.

10. A conveyer system having a pivoted switch point, means normally holding the switch point in a predetermined position but permitting it to move therefrom, and movable stop means disposed adjacent to

- the switch point for arresting a carrier moving along the switch point when the latter is out of normal position, the position of the stop means being unchanged by movement 5 of the switch point except when a carrier rests upon the latter, said stop being constructed to release such carrier only after the switch point has resumed its normal position.
- 10 11. A conveyer system having a main track, a branch track, along which carriers approach the main track, a switch point pivotally connected to the end of the branch track and having its free extremity normally 15 in engagement with the main track, and a stop member having an abutment element so disposed as to arrest a carrier moving along the switch point when the latter is out of normal position, said stop member 20 being independent of and normally unconnected to the switch point, said abutment element being adapted to retain such arrested carrier until the switch point is fully 25 restored to normal position.
- 25 12. A conveyer system comprising a pivotally supported switch point, a spring normally holding said point with its free extremity in predetermined position, and a movable stop member having an abutment 30 element so disposed as to arrest a carrier moving along the switch point when the latter is out of normal position and to follow the switch point as the latter returns toward 35 normal position to avoid premature release of the arrested carrier, the position of the stop member being unchanged by movement of the switch point except when a carrier rests on the latter.
- 40 13. A conveyer system comprising a movable switch point, spring means normally holding the switch point in predetermined position, a freely suspended member having an abutment element normally positioned to arrest a carrier moving along the switch 45 point when the latter is out of normal position, and to follow the switch point as the latter moves back toward normal position, and a stop to limit movement of the abutment element whereby to release the arrested 50 carrier substantially at the instant that the switch point resumes its normal position.
- 55 14. A conveyer system comprising a movable switch point and spring means normally holding it in predetermined position, a freely suspended supporting member carrying an arm provided with an abutment element 60 normally so disposed as to arrest a carrier moving along the switch point when the latter is out of normal position, and spaced stops disposed on opposite sides respectively of the suspended supporting member for limiting the movement of the abutment element in either direction from normal.
- 65 15. A conveyer system comprising a pivoted switch point movable in a substantially horizontal plane, spring means normally holding the switch point in predetermined position, a supporting member freely suspended to swing about a substantially horizontal axis in a plane above the plane of movement of the switch point, a horizontal arm carried by the supporting member and terminating in an abutment shoulder lying substantially in the plane of the switch point and adapted to permit carriers to pass 70 freely along the switch point when the latter is in normal position but to arrest carriers so moving when the switch point is not in normal position, and a pair of depending stops for limiting swinging movement of 75 the supporting member in either direction from normal.
- 80 16. A conveyer system having a pivoted switch point, and a stop device, the switch point being movable relatively to the stop device whereby to cause a carrier moving along the switch point to engage the stop device and thereby to be brought to rest, the normal position of the stop device remaining unchanged when the switch point is shifted.
- 85 17. A conveyer system having main and branch tracks, a pivoted switch point forming a continuation of the branch track, the end of said switch point normally engaging the main track but being movable away therefrom, and a stop device so positioned that when the switch point is moved away from the main track a carrier moving along said switch point will engage the 90 stop device and thereby to be brought to rest, the stop device normally occupying the same position regardless of the position of the switch point.
- 95 18. A conveyer system having a plurality of tracks, a switch point forming a continuation of one track, means normally holding said switch point in engagement with the other track, and a stop device, the switch point being movable away from said latter 100 track and relatively to the stop device whereby to cause a carrier moving along the switch point to engage the stop device and thereby to be brought to rest, the stop device normally maintaining its position 105 unchanged when the switch point is moved toward or away from the track.
- 110 Signed by me at Syracuse, N. Y., this sixteenth day of April, 1923.
